UNITED STATES PATENT OFFICE.

LESLIE ELDRIDGE VASS, OF HENDERSON, KENTUCKY.

HAIR-CLIPPER.

1,245,833.

Specification of Letters Patent.

Patented Nov. 6, 1917.

Application filed August 29, 1916. Serial No. 117,532.

To all whom it may concern:

Be it known that I, LESLIE E. VASS, a citizen of the United States of America, residing at Henderson, in the county of Henderson and State of Kentucky, have invented new and useful Improvements in Hair-Clippers, of which the following is a specification.

This invention relates to barbers' appliances and has particular application to improvements in hair clippers.

The chief characteristic of this invention resides in the provision of a device of this character in which the hair clipper is adapted to cut the hair when moving the clipper in two directions whereby the usual reverting of the clipper to the starting position will be eliminated thus producing an article which will cut the hair with a minimum expenditure of labor. In the hair clippers with which I am familiar, there is one cutting edge which only permits the cutting of the hair when moving the clipper in one direction, thus necessitating the disengaging 25 of the clipper from the hair to revert the same to starting position. In carrying out my invention I propose to eliminate this unnecessary movement of the clipper when reverting to starting position by providing 30 two edges of the clippers with a cutting blade whereby the clipper may be reciprocated over the hair and the cutting operation continued with the forward or rearward movement of the clipper.

Another characteristic of this invention is to provide a hair clipper having a comb associated with either of the stationary blades, the comb being adjustably mounted upon the clippers and adapted to engage the 40 depth or length of the clipper upon the head.

Another characteristic of this invention is to provide a hair clipper in which the handles for operating the clipper are reversely mounted thereupon whereby either cutting edge of the clipper may be presented to clip the hair when moving the clipper forwardly.

Another characteristic of this invention resides in the provision of the device of this 50 character which is simple, efficient and durable in its construction and which may be manufactured at a nominal cost.

Other characteristics of the invention will

appear as the specification is read in connection with the accompanying drawings, in 55 which:—

Figure 1 is a side elevation of the clipper constructed in accordance with my invention.

Fig. 2 is an end elevation. 60

Fig. 3 is a vertical central section of Fig. 1.

Fig. 4 is a horizontal section taken on the line 4—4 of Fig. 1.

Fig. 5 is a bottom plan view of the clipper showing the comb in reversed position. 65

Referring to the drawings in detail, my invention comprises a rectangular plate 1 which has the opposite longitudinal edges thereof provided with pointed teeth 2 which 70 constitute the stationary blades 3. Formed upon the upper side of the plate 1 and extending upwardly therefrom is a circular standard 4, the standard being provided centrally thereof with a longitudinally extending bore 5. Disposed at diametrically opposite points upon the standard 4 adjacent its connection with the plate are the rectangular openings 6 through which the mechanism for moving the blades is adapted to extend, as will be hereinafter described. The upper side of the plate 1 is formed with longitudinally extending spaced ridges 7 which are disposed upon opposite sides of the standard 4 and arranged at the longitudinal 75 medial portion of the plate, while disposed upon the opposite side of the ridges and adjacent the opposite ends of the plate 1 are the upstanding pins 8. Mounted upon the plate 1 and upon opposite sides of the standard 4 are the movable blades 9 which have their outer edges provided with the teeth 10, the teeth being of a similar construction as those of the blade 3. The movable blades 9 are provided with rectangular openings 11 80 disposed adjacent their opposite ends which are adapted to receive the respective pins 8, the pins limiting the longitudinal movement of the blades in either direction. The movable blades 9 are further provided at their 85 inner edges with the arcuate recesses 12 to accommodate the standard 4 and at the same time to permit the movement of the blades.

Arranged upon the standard 4 and overlying the movable blades 5 is a cover plate 105 14 which is provided centrally thereof with

a circular opening 14' which is adapted to receive the standard while the opposite ends of the plate are provided with the ears 15 which are secured to the opposite ends of the plate 1 by means of the screws 16.

The upper ends of the standard 4 are formed with a squared socket 17 in which is mounted a squared projection 18 formed on the underside of the annular head 19 of the stationary handle 20. Extending through the bore 5 of the standard 4 and having its lower end journaled within the plate 1 is a shaft 21 the shaft being of such a length as to project beyond the upper end of the standard and terminating in a squared head 22. The upper head of the shaft 21 is adapted to extend through the annular head 19 of the handle 20, the squared head confining the handle upon the shaft as will be understood. The shaft 21 is formed adjacent its lower end with diametrically opposed pins 23 which are adapted to extend through the openings 6 formed in the standards and have their outer ends disposed within the notches 12'. It will be seen from this construction that when the shaft is oscillated the blades 9 will be reciprocated in opposite directions.

Mounted upon the squared head 22 of the shaft 21 is the head 24 of the movable or operating handle 25, the head 24 being provided with a squared opening which receives the head 22 whereby upon movement of the handle 25, movement will be imparted to the shaft 21. The confronting faces of the heads 19 and 24 are provided with annular grooves 26 which coöperate to form a socket to receive the coiled spring 27, the opposite ends of the spring being secured to the heads 19 and 24 to cause the spring to exert its tension and normally retain the handle 24 in spaced relation to the handle 20.

To retain the handle upon the shaft 21, I provide the standard 4 with an upright 28 which is detachably secured to the standard 45 by means of the screw 29. The outer end of the upright 28 extends beyond the upper end of the screw and is provided with an annularly disposed head 30 which overlies the head 24 formed on the handle 25 and has its lower or inner face cupped to receive the said head and at the same time to permit the free movement of the head when actuating the handle 25. The head 30 and the upright 28 being detachably secured to the standard permits the ready removal of the handle when moving the handle to reversed position as will be hereinafter described.

To gage the length of and to erect and present the proper position of the hair to be cut, the underside of the plate 1 is provided with a substantially U-shaped frame 31, the opposite ends of which are pivotally mounted upon the screws 16, the medial portion of the frame being provided with suitable securing means for holding a comb 32 of any

suitable construction, the securing means permitting the detaching of the comb to facilitate the cleaning or interchanging thereof. The frame 31 being hingedly mounted for swinging movement permits the comb to be moved to opposite positions with relation to either of the blades 3, the comb assuming different positions with relation to the blades for the cutting of long or short hair as is clearly shown in the drawings.

In operation, the handles 20 and 25 are gripped in the usual manner, the fingers engaging the hook 33 whereby upon compressing the hand, the movable handle 25 will be moved toward the stationary handle against the tension of the coil spring 27. Upon moving the handle 25, the shaft 21 will be partially rotated thereby causing the pin 23 to engage the notches 12' thus causing the movable blades 9 to move longitudinally of the plate 1 and in reverse directions. It will be evident that upon relieving the handle 25 of compression, the spring will exert its tension to move the handle into open or normal position thereby causing the shaft to partially rotate in an opposite direction thus causing the movable blades to again reciprocate in a reverse direction, the pins 8 limiting the movement of the blades as has been described. In providing the plate 1 with the ridges 7, I insure the top movement of the blades and prevent the accidental clogging of the same. When the blades 9 are moved longitudinally of the blades 3, the pins formed on each of the blades will perform the cutting operation in a manner similar to that of the ordinary hair clipper.

It will be manifest from the foregoing that when the clipper is applied to the hair, the operator may actuate the movable blades to cut the hair when moving the clipper either forwardly or rearwardly and thus eliminating the unnecessary movement of bringing the clipper to its starting position as will be understood. When using the comb 32, in connection with the clipper, the comb being arranged in advance of the clipper, the hair will be directed and disposed in proper positions to facilitate the cutting thereof with the clippers. By providing a supporting frame for the comb of this particular construction it will be evident that when the comb is disposed in advance of one of the blades, it will be disposed relatively close to the said blade thus causing the blade 115 to cut only a short length of the hair while when the comb is in the reverse position at the opposite stationary blade, it will be disposed in greater spaced relation to the blade thereby causing the blade of the clipper to 120 cut hair of a greater length. It will thus be seen that I have provided two adjustments for the comb with respect to the cutter so as to cut the hair at different lengths.

When it is desired to use only one of the 130

stationary blades or one side of the cutter, the handles are so mounted as to permit the reversion thereof by the removal of the uprights 28 and the head 30.

5 It is thought from the foregoing taken in connection with the accompanying drawings that a construction and operation of my device will be apparent to those skilled in the art, that minor changes in size, shape, 10 proportion and minor details of construction may be made without departing from the spirit and scope of the appended claims.

What I claim is:—

1. The combination with a hair clipper embodying a fixed blade having opposed cutting edges, a movable blade arranged to reciprocate across each edge, and means for reciprocating said movable blade, of a yoke 20 swingingly mounted on said fixed blade, a comb associated with said yoke, lugs projecting from said yoke and positioned between the teeth of the comb for holding the latter mounted on said yoke, said yoke being adjustable to arrange the comb in juxtaposition with either edge of said fixed blade.

2. A hair clipper embodying a fixed blade having opposed cutting edges, a standard rising from said blade and provided with a central bore, and a transverse recess intersecting said bore, a shaft positioned within said bore and journaled in said fixed blade, a pin extending transversely of the shaft and arranged in said recess, a movable blade arranged to reciprocate across each cutting edge of the fixed blade, said blades having a notch to receive the extremity of said pin, whereby said movable blades are reciprocated in opposite directions simultaneously

when the shaft is rotated, and means for rotating said shaft.

3. A hair clipper embodying a fixed blade having opposed cutting edges, a standard rising from said blade, and having a central bore, a shaft journaled in said blade and positioned within said bore, a movable blade 45 arranged to reciprocate across each cutting edge of the fixed blade, a connection between said shaft and movable blades for simultaneously operating the latter in opposite directions when the shaft is rotated, a fixed 50 handle secured to said standard, a relatively movable handle secured to said shaft for rotating the latter, and means for normally maintaining said handles spaced.

4. A hair clipper embodying a fixed blade 55 having opposed cutting edges, a standard rising from said blade and having a central bore, a shaft journaled in said blade and positioned in said bore, a movable blade arranged to reciprocate across each cutting 60 edge of the fixed blade, a connection between said shaft and movable blades for operating the latter simultaneously in opposite directions on rotation of the shaft, a handle removably associated on said standard and 65 fixed relative thereto, a second handle removably associated with the shaft and adapted to rotate the latter when moved toward and away from said fixed handle, means for normally holding said handles 70 spaced, and said handles being capable of being reversed, to permit either cutting edge of the clipper to be used for moving the clipper forwardly.

In testimony whereof I affix my signature. 75

LESLIE ELDRIDGE VASS.
